poration of Wisconsin

Application February 10, 1948, Serial No. 7,416

18 Claims. (Cl. 51—67)

1

This invention relates to improvements in methods and apparatus for sanding and polishing, and particularly for refinishing various workpieces such as spools and the like.

The apparatus and method herein disclosed are improvements upon the disclosures of Mat-teson Patent No. 1,159,696 of November 9, 1915, and Lippold Patent No. 2,119,954 of June 7, 1938.

The invention will be particularly described with reference to the refinishing of spools such as are used for natural or synthetic silk and require to be resurfaced before being re-used. In use, the spool heads become roughened or nicked or gummed and before they can be re-used, they must be restored to substantially perfect smoothness to avoid injury to the threads wound thereon and discharged over the spool heads.

It will be noted that the new finishing methods herein disclosed may be largely or entirely performed by hand.

The objects of the invention include the provision of abrasive strips which are pre-formed to fit the contours of the work and are supported at such contours from the work-engaging or abrasive side of the strip in order to afford completely flexible and yielding pressure support of the rear face in pressure engagement with the work. It is a further object of the invention to effect final finishing by automatically controlled burnishing operations engaging particularly those surfaces of the work contacted by the yarn threads as they are delivered from the spools.

The mechanical features of the present device may constitute a separate machine made for the special purposes hereof, or they may be embodied in an attachment applicable to existing machines of the type illustrated in the patents above identified.

Other objects of the invention will be more clearly apparent in the light of the following disclosure.

In the drawings:

Fig. 1 is an end elevation of the machine embodying my invention.

Fig. 2 is a front elevation of the machine shown in Fig. 1.

Fig. 3 is an enlarged fragmentary detail view in perspective showing a sanding pad mounting and abrasive sheet guide.

Fig. 4 is a view in horizontal section through the guide illustrated in Fig. 3.

Fig. 5 is a view in rear elevation partially broken away and illustrating the sanding pad mounting.

2

Fig. 6 is an enlarged fragmentary detail view in plan of burnishing apparatus as viewed from the position indicated at 6—6 in Fig. 2.

Fig. 7 is a view taken on the line 7—7 of Fig. 6.

Fig. 8 is a view taken on line 8—8 of Fig. 7.

Fig. 9 is a view taken on line 9—9 of Fig. 7.

Fig. 10 is a fragmentary view in rear elevation showing the locking arrangement for the reciprocating and tilting sub-frame.

Fig. 11 is a fragmentary detail view on an enlarged scale taken on line 11—11 of Fig. 10.

As in the devices of the prior patents above identified, the basic machine used comprises a turret shaft 10 mounted in a suitable frame and supporting head stock 11 and tail stock 12. The shaft is slowly rotated from motor 13 through the belt drive 14, and the double worm gear reduction 15. The head stock 11 carries live spindles 16 which are equipped with pulleys and continuously driven by a belt 17 which passes circuitously about the several pulleys which are remote from the idler pulley 18 and the driving pulley 19, the latter being mounted on the shaft 20 primarily driven from motor 13 by belt 14. In the course of turret rotation that spindle 21 driving pulley which is at the loading station A (Fig. 1), lies between the driving pulley 19 and the idler 18 and is therefore out of contact with the belt. At this point, the rotation of the spindle is arrested by a brake shoe 21 which operates on the sheave 170 with which each spindle is provided (Fig. 2).

The dead spindles 23 mounted in the tail stock 12 are biased toward spindles 16 but are provided with annularly beveled retracting cam followers 24 which, in the course of turret rotation, engage the surfaces of the complementary stationary cam member 25 to retract successive dead spindles. This allows the release of the respective finished workpieces and, as the turret continues to revolve and each cam follower 24 clears cam 25, a fresh workpiece is picked up from the supports 26 at loading station A in which the workpiece has been placed by the operator. The workpiece shown in Fig. 2 at 27 comprises, for the purposes of this disclosure, a spool having heads 29.

As the turret revolves, the spool in general and the heads in particular are subjected to progressively finer abrasive action and ultimately to a burnishing operation by means now to be disclosed.

Suspended by the links 30 at the rear of the machine is a bar 31 upon which are mounted the arms 32 connected by tie rod 33 at their lower

ends and curved forwardly at their upper ends, the assembly constituting a sub-frame for the support of the sanding devices. The entire sub-frame may be oscillated to an inoperative position shown in dotted lines in Fig. 1, being pivotal on axis of the bar 31 for the purpose of replacing worn abrasive and making adjustable parts more readily accessible. In moving from its dotted line position to its full line position in Fig. 1, the center of gravity of the sub-frame passes through a vertical line through said axis. Thus the sub-frame is held by gravity bias in either of the illustrated positions.

During the normal use of the machine, the sub-frame comprising arms 32 is locked in the position in which it is illustrated in full lines in Fig. 1. The locking arrangement, which must accommodate lateral reciprocation of the sub-frame as hereinafter described, is effected through the mechanism best shown in Figs. 10 and 11 on sheet 2 of the drawings.

The cross bar 400 of the sub-frame is reciprocably confined in a way provided by rear guide members 97 fixed on the forwardly projecting arms 98 carried by standards 99 of the main frame. With the guide members 97 coact guide members 100 mounted on the same arm 98 and yieldable thereon under compression of spring 101 (Fig. 11). The guide members 100 are also oscillatable on the supporting arms 98 from the position shown in full lines in Fig. 10 to the positions shown in dotted lines in such view. In order that they may oscillate in unison, they are connected by a link 102 which is pivoted to one of the guide members 100 at 103, above its center of oscillation and is pivoted to the other upon a clamp bolt 104 which is located below its center of oscillation. This clamp bolt has a handle 105 by means of which the eye 106 at the end of link 102 may be clamped to the member 100, or released to permit swinging movement. When the clamp bolt 104 is turned to relax its compression on the eye 106, the same handle may be used to oscillate counterclockwise the guide member 100 which is at the left as viewed in Fig. 10. With the guide members 100 swung to a horizontal position, the cross bar 400 of the sub-frame will be released whereby the sub-frame may be oscillated from its full line position to its dotted line position as shown in Fig. 1.

With the guide members in place to confine the cross bars 400, the sub-frame will be held in its operative position but will be permitted free vibration laterally.

The lateral vibration of the sub-frame is actually oscillatory about the upper centers of link 30 but its amplitude is so slight that it may be regarded as vibratory reciprocation. For effecting such vibration, the link 30 which is at the left as viewed in Fig. 2, is provided with a bell crank arm at 28 slotted to receive a connection, adjustable as to radius, with the pitman 34 which is reciprocated by an eccentric 35 on the shaft 36 which comprises an intermediate shaft in the double worm gear reduction mechanism 15. As shaft 36 rotates, the entire sub-frame is moved to and fro with an amplitude determinable by the point at which the pitman is connected to the bell crank 28.

The upwardly extending arms 32 of the sub-frame have their upper ends cross-connected at various points by bars 40 (Fig. 2) which support the various abrasive webs and the guides therefor, the latter being more particularly illustrated in Figs. 3 to 5. The abrasive webs 41, which may

comprise either paper or fabric, with or without abrasive grains on the surface, are supplied in rolls 42 respectively carried by the arm extensions 43 and rods 44. For at least the first two webs encountered by the workpieces during turret rotation, I prefer to use fine and very fine grades of abrasive. The third web may comprise an unsanded fabric such as burlap for polishing. The mounting and treatment are identical with the exception that the abrasive web 41 is preferably scored to facilitate its folding sharply along the lines indicated at 45, 46, 47 in Fig. 3 and Fig. 4. Carried by each of the cross bars 40 is a bracket 50 clamped thereto as shown in Fig. 3 and Fig. 4. This bracket includes a guide surface at 51 which engages the back side of the abrasive web 41 adjacent the right angle fold 45 therein. For holding the web releasably to such surface, I provide an eccentrically mounted clamping disk 52 freely rotatable on the headed pintle 53 and adapted, when its side of greater radius is presented to surface 51, to clamp the web 41 thereto as shown in Fig. 4. The clamping eccentric 52 is freely rotatable to and from clamping position under the manipulation of the operator.

The pintle 53 has a shoulder at 54 clampingly engaged with an eccentric disk 55 whereby such disk is held to the clamping surface 56 of the bracket arm 57 under pressure provided by the nut 58 on the threaded end of the pintle 53. This disk is set to any desired degree of rearward projection as viewed in Fig. 4 to fit within the channel formed in web 41 by the pre-scored creases 45, 46 and 47. For a deeper channel, the eccentric disk 55 would be adjusted to present its greatest radius rearwardly. For a less deep channel, it would be adjusted to present a portion of lesser radius to engage in the channel. In any such position, it is held by clamping pressure developed in the tightening of nut 58.

A transverse bore through the pintle 53 receives the guide rod 59. This rod carries a finger 60 which lies behind the channel of the abrasive web to hold such channel properly fitted about the forming disk 55. At its forward end the guide rod 59 has another finger at 61 engaging the peripheral portion of disk 55 which lies at the front. Thus, in all positions of the disk, the guide rod 59 is self-adjusting to provide the desired backing support between finger 60 and the abrasive web.

Due to the operation of the disk 55 and the coacting surfaces of the blanket clamp 53, the several webs fed from the supply spools will, in each instance, be formed to provide forwardly facing channels in which the abrasive surface of the web lies innermost. The channels will increase in depth progressively as shown at 62 in Fig. 1.

Immediately below each of the bars 40, the space between the sub-frame arms 32 is spanned by the pintle rods 64 which support the respective pads which back the abrasive webs. These pads are, for the purposes of the present disclosure, arranged in sets of three individually adjustable and individually pivoted to the pintle rods 64. There is a wide central pad at 65 and narrower pads 66, 67 at each side thereof, as best shown in Fig. 5. Each pad comprises a head 68 which supports broom corn or the like at 69 as taught in the prior patents aforesaid. For the purposes of the present invention, however, the broom corn is covered with a sheet of sponge rubber or other resilient material at 70, thereby

providing a smoother support for the abrasive web and a better distribution of flexibly yielding pressure thereto. The pressure is furnished by the resilience of the broom corn and the adjustment of the appropriate screw or set screws 71, these being threaded through sockets provided in the bracket 50.

The channels formed in the abrasive webs are accommodated by the space between the central pads 65 and the margin pads 66, 67. The broad surface of the web between the channels is supported on the resiliently yielding facing 10 of the central pad 65.

While the sanding operations are calculated to remove nicks and to smooth all of the major surfaces of the spool or workpiece 27, it will be noted that there are some areas which may not adequately be polished. Accordingly, I provide for a series of burnishing operations by the mechanism best shown in Figs. 6 to 9, the location of which is illustrated in Fig. 1.

Reference has been made to the links 30 by which the sub-frame is pivoted for lateral reciprocatory vibration. These links are carried on bars 75 and in order that the entire apparatus may be handled unitarily as an attachment to existing machines, I prefer to extend these same bars 75 inwardly as shown in Fig. 6 to provide a support for the cross bar 76 upon which the burnishing mechanism is carried.

In the path of the spools or other workpieces as they revolve with the turret and rotate upon their axes, I provide at least one, and preferably a succession of burnishing members 77 (Figs. 6, 7 and 9). For the purposes of the present device, each of these is preferably semi-cylindrical as best shown in Fig. 6 and each is mounted individually on a leaf spring 78 carried by an arm 79 of a clamping bracket 80 fast to the bar 76. For the particular purpose of burnishing the spool 27, I design these burnishing tools 77 to fit those surfaces of the spool immediately adjacent the bases of the flange 29 thereto, since the abrasive material cannot have adequately been forced into the angle between the flange and the body of the spool.

There remains the problem of polishing or burnishing all surfaces on the rounded periphery of the flange 29.

For this purpose, I provide a separate clamping bracket 83 at each end of the spool. Intermediate the ends of these respective clamping brackets, I provide fulcrum pins 84 and on these pins I pivot arms 85 urged upwardly by compression springs 86 seated upon the outer ends of brackets 83.

Each of the arms 85 comprises means such as the ears 87 for the support of the burnishing tool 88 which is fulcrumed on the cross pin 89 and adjusted by set screws 90. As best shown in Fig. 6, each tool 88 has a groove 91 which is V-shaped in cross section and relatively deep at the end first engaged by the flanges of spool 27 but gradually decreases in depth until it runs out completely at the remote end of the tool. Where the flanges of the workpiece first encounter the tools, the surfaces of the V-shaped groove will engage the flanges near the flat faces thereof as shown in Fig. 8, but as the grooves decrease in depth, the point of engagement will gradually move about the arc of the periphery of the flange until, before the flange leaves the tool, the flat surface of the tool is engaged with the extreme central periphery thereof.

Since the tool is bodily yieldable under bias of

compression spring 86, it is desirable to push the tool out of the way in the event that particular spindles of the turret carry no workpiece. For this purpose, each of the arms 85 is desirably provided with a bracket 93 carrying a cam 94 which, during normal operation, is spaced from the collar 22 of live spindle 16, but is so located that it will engage such spindle for the positioning of tool 88 in the event that the spindle carries no workpiece 27.

While the method involved will probably be apparent to those skilled in the art from the foregoing description of the apparatus preferably used in the practice of such method, it may be desirable to summarize the method briefly as follows:

Insofar as the abrasive or polishing webs have any substance, they are preferably scored where they are to fold in passing over the supporting pads to make the channels in which the flanges of the spools are engaged during the polishing operation. The scoring subdivides the webs into spool shank or body engaging zones and zones conformable to the outer periphery and both faces of the spool heads.

The materials thus preliminarily scored are fed over resiliently yieldable supporting surfaces which are spaced to receive the channels formed in the webs by web-supporting and deforming members adjustably fitted within the channels. By supporting the abrasively lined channels from within, I am able to permit the abrasive web to yield outwardly in all directions.

With reference to the abrasive web or webs thus supported, a succession of rotating spools are passed along the curved paths into and out of contact with the abrading surfaces of successive webs with the peripheries of the spool heads or flanges in the pre-formed channels of the webs, while yielding pressure is applied from the outside of the web to hold their abrasive surfaces to the work in the several zones above described.

After being sanded with abrasive webs of progressively increasing fineness, the final operation performed by the last web in the series may be a polishing operation, for which purpose the web may comprise an unsanded fabric such as burlap or the like. A fabric web does not need preliminary scoring, but the formation of the channels therein and the relative movement of the spools with regard thereto is identical to that above described.

Thereupon, during the continued rotation of the spools and their continued movement upon an orbital path, they come into contact with yieldably supported burnishing or polishing tools, the last of which comprises means for exerting burnishing pressure simultaneously upon opposite sides of the rounded peripheries of the spool flanges and thereupon progressively shifting the points of application of such pressure toward the peripheral center lines of the flanges during the continued application of such pressure to the flanges.

The result is a workpiece which is not merely perfectly smooth throughout all portions of its surfaces contacted by the thread wound on the spool, but is actually highly polished, thereby virtually eliminating injury to the thread during its unwinding from such a spool.

In the preferred practice of the method herein disclosed, the circular flanges of the workpieces move into and from the channeled, abra-

sive webs in the course of an arcuate path of workpiece advance and during continued workpiece rotation. In order to assure the abrasive action of the sides of the channel on the opposite faces of the flanges, relative movement between the channeled abrasive material and the flanges is made to occur, whereby first one side of the channel and then the other is pressed against the corresponding opposite faces of the flange.

I claim:

1. In a sander, a support for a web of polishing material comprising a backing composed of multiple layers of overlapping individually yieldable strands aligned in the direction of abrasion and having a mounting at one end and a flexible pad of sheet material materially thinner than the backing and overlying said strands and upon which such web is supported.

2. A support for an abrasive web comprising a mounting member, a plurality of resilient strands arranged in multiple overlapping layers connected at corresponding ends to said mounting member, free at their opposite ends and aligned in the direction of abrasion, and a sheet of sponge rubber materially thinner than the layers of strands resting on said strands and constituting a support for said web, said sheet being also connected at one end to the mounting member and being free at its opposite end.

3. In a machine for treating workpieces with an abrasive web, a pad support for the web comprising a plurality of pads having edges mutually spaced, and an associated former disposed opposite the space between the pads and approximately corresponding in width thereto; said former being adapted to channel a web and to position the channel in the space between said pads with its abrasive surface at the interior of the channel.

4. The combination with a pair of pads having edges mutually spaced and adapted to receive between them the channel of an abrasive web, of a web forming device disposed in alignment with the channel and offset longitudinally from the effective portion of the channel, said forming device comprising a flange having a thickness approximately corresponding to the width of the channel, and a complementary surface spaced from said forming device and between which and said flange a portion of the channel of the web extends.

5. In a machine for abrasively finishing flanged workpieces with a channeled abrasive web, the combination with a bracket provided with a clamping pintle, of a channel former comprising a disk eccentrically mounted on the pintle and positioned to enter the channel of the abrasive web to determine the dimensions thereof, said pintle having a shoulder in clamping engagement with said disk and determinative of its penetration into said channel according to the eccentric position in which the disk is clamped.

6. The combination set forth in claim 5 in which said bracket has adjacent said disk a clamping surface approximately normal to the face of the disk for positioning an unchanneled portion of the web; and an eccentric clamp is rotatable on a portion of said pintle to and from clamping engagement with a web contacting the clamping surface aforesaid.

7. In a machine for abrasively finishing flanged workpieces with a channeled abrasive web, the

combination with a bracket having a short arm provided with a terminal clamping face and a longer arm spaced therefrom, of a pintle provided with a shoulder and a head and projecting from the longer arm transversely in front of said clamping face, an eccentric web channel-forming disk rotatable upon the pintle between said arms and having a hub portion clampingly engaged by the flange of the pintle, and an eccentric clamping member mounted on the pintle between the shoulder and the head and oscillatable thereon to and from clamping movement toward said face.

8. The device of claim 7 in further combination with a rod reciprocable longitudinally of the longer arm and provided with fingers spaced to receive said disk and a channeled web formed partially by pressurized folding action on the web between the disk and the arms, one of said fingers being substantially engaged with said disk at a point diametrically remote from said web, and the other being positioned by the finger first mentioned to hold the channel of said web in proximity to the forming portion of said disk.

9. An attachment for a sanding machine having a turret and multiple spindles for spools to be sanded, said attachment comprising a pair of spaced arms, cross members connecting said arms in proximity to the path of rotation of said spindles, and web supports comprising pads spaced to receive the flanged heads of spools carried by the spindles, said pads being provided with supports from said members, and channelling means mounted on the respective members and each comprising a channel former opposite the space between two pads and offset from the point of entry of a spool head between such pads, each such former being adapted to engage a channeled abrasive web within its channel and thereby to hold its channel in the space between said pads.

10. The combination set forth in claim 9 wherein each channel former comprises a disk and an eccentric mounting for said disk upon which the disk is rotatably adjustable, said mounting including means for the clamping of the disk in predetermined adjustment whereby the depth of the channel formed thereby is determinable.

11. The combination set forth in claim 9 wherein each channel former comprises a disk and an eccentric mounting for said disk upon which the disk is rotatably adjustable, said mounting including means for the clamping of the disk in predetermined adjustment whereby the depth of the channel formed thereby is determinable, together with an abrasive web clamp disposed in proximity to each disk, each such clamp including a bracket arm having a terminal clamping surface and an eccentric member pivotally movable for engaging an intervening abrasive web with such surface.

12. In a machine for finishing spools having a revolving turret and spool-supporting spindles rotatable on axes transverse respecting the path of advance of the turret, the combination with pads for the support of abrasive webs, of formers for channelling said webs, said pads having spaced edges adapted to accommodate the web channels therebetween, and a burnishing tool having hard surfaces and provided with a yieldable mounting supporting such tool for contact with a rotating spool in the path of advance thereof upon said turret beyond the point of engagement with said web, said turret comprising means for automatically advancing the rotating spool from engagement with the web supported

by the pads to engagement with the burnishing tool.

13. A machine of the character described comprising the combination with a frame and a work spindle mounted on the frame, of a support for an abrasive web including a web channelling former, a sub-frame mounted on the machine frame and comprising a carriage relatively movable in a direction transverse respecting said channel, and means for moving said carriage in said direction for engaging the sides of said channel with the faces of a flanged workpiece.

14. A spool finishing machine comprising a spindle for rotating a spool having a flange in combination with a pad for the support of an abrasive web for sanding the spool, said pad having spaced portions adapted to accommodate the flange, a web-channelling former adjacent the pad for holding the channel or the channeled web in the space between the pad portions aforesaid, a carriage movable respecting the spindle in a direction axially thereof and transverse with respect to the channel of said web, supports for the pad and the former on said carriage, and means for reciprocating the carriage whereby to bring opposing faces of the channeled web into contact with opposing faces of the spool flange.

15. A method of polishing spools for thread, such method consisting in, rotating a spool while moving it upon an arcuate path, bringing said spool into abrasive contact with a channeled abrasive web, carrying its head into the channel of the web, and applying yielding pressure to the web for holding its abrasive surfaces against the spool.

16. The method recited in claim 15 in combination with the further step of moving the channeled web axially respecting the spool while the spool flange is disposed within the channel and the spool is in rotation, thereby bringing abrasive surfaces at opposite sides of the channel into contact with opposite faces of the spool flange.

17. In a machine for finishing tools having a revolving turret and spool supporting spindles rotatable on axes transverse respecting the path of advance of the turret, the combination with pads for the support of abrasive webs, of formers for channeling said webs, said pads having spaced edges adapted to accommodate the web channels therebetween.

18. A surface compacting burnishing tool for a rotating workpiece of circular cross section and convex periphery, said tool comprising an elongated member having a top surface and a groove in said top surface which progressively varies in depth from a relatively deep portion to a point where the groove merges with said top surface,

the upper margins of the groove walls being gradually convergent throughout their length from the deep end of the groove to said point where the groove merges with the top surface, said top surface and groove walls constituting hard, surface-compacting faces to compact the surface material of the workpiece rotated thereagainst, said top extending beyond the point where the groove merges therewith to constitute a flat burnishing face, together with means for the support of a workpiece, said means comprising means for rotating the workpiece on its axis of rotation and means for bodily moving the workpiece on a path transverse to said axis, means for supporting the tool in said path whereby the incidence of coaction of the workpiece with the tool is transverse to said axis and aligned with the elongation of the tool, said means including resilient yieldable means to bias the tool against the workpiece, the path of the workpiece intersecting the groove in the tool whereby the convex periphery of the rotating workpiece enters the groove of the tool and moves progressively from one end of the groove toward the other whereby burnishing pressure is progressively angularly transferred about said convex periphery, said path extending beyond the point where the groove merges with the top surface of the tool whereby the crown of the workpiece is burnished on the top surface of the tool.

CARL J. LIPPOLD.
